UNITED STATES PATENT OFFICE.

ALEXANDER B. KUPSCHE, OF CHICAGO, ILLINOIS.

RADIO RECEIVING APPARATUS.

Application filed August 15, 1924. Serial No. 732,152.

This invention relates to improvements in radio receiving apparatus and consists of the matters hereinafter described and more particularly pointed out in the appended claim.

One of the objects of the present invention is to provide a novel and improved apparatus, which not only includes suitable means for the reception of radio waves but also has combined therewith an illuminating device, shaded by a part of the receiving apparatus and so arranged as to direct the rays from said illuminating device upon the other parts of apparatus so that they may be most conveniently manipulated.

A further object of the invention is to provide an improved aerial for the receiving set which is so arranged as to provide a shade for the illuminating device, capable of being tilted in a direction adapted for the best reception and also for the desired disposition of the light rays.

Still a further object of the invention is to so arrange the various parts thereof, that the apparatus is symmetrically balanced and presents an ornamental and pleasing appearance as well as providing a device of great utility.

These objects of the invention, as well as others together with the many advantages thereof will more fully appear as I proceed with my specification.

In the drawings:

Fig. 1 is a view in side elevation of an apparatus embodying my invention, with parts shown as broken away to more clearly illustrate the interior construction.

Fig. 2 is a horizontal sectional view as taken on the line 2—2 of Fig. 1.

Fig. 3 is another horizontal sectional view as taken on the line 3—3 of Fig. 1.

Fig. 4 is a detail horizontal sectional view on an enlarged scale as taken on the line 4—4 of Fig. 1.

Fig. 5 is a top plan view on a reduced scale, of the combined aerial and shade of the apparatus.

Fig. 6 is a perspective view of a certain block embodied in the apparatus and which will be more fully described later.

Referring now in detail to that embodiment of the invention illustrated in the accompanying drawings 1 indicates as a whole the horizontally disposed hollow base of the apparatus, which is preferably made of a suitable insulating material. Said base in-

cludes top and bottom spaced plates 2 and 3, respectively, which are connected together at their edges by an upright wall 4 and said base has an enlarged central body part 5 with oppositely disposed smaller rounded end extensions 6 and 7, respectively. The base 1 is of such an area as to provide a stable support for the apparatus as a whole and so that the same will not mar or injure any table top or the like upon which it is placed I provide on the under side thereof, a plurality of yielding feet 8, or a felt pad which may serve as well for said purpose.

Arising from the rounded end extensions 6 and 7 are sockets 9 and 10 adapted to receive a detector tube 11 and an amplifying tube 12, respectively, of any well known kind, used in radio receiving sets. Preferably the base 1 is made of a molded dielectric material so that said sockets are made integral with said top plate.

Arising from the central body part 5 of the base is a plurality of upright legs 13 arranged in front and rear pairs respectively, all equally spaced about a common vertical axis. The top ends of said legs, which are formed to more closely approach said axis are secured in any suitable manner to the cutaway corners of a rectangular block 14 as shown in Figs. 1 and 4, said block being shown in perspective in Fig. 6. In the front and rear faces of said block are vertically extending grooves 15—15 respectively, and in the side faces of said block are vertically extending grooves 15^a—15^a which are of a greater depth at their top end than they are at their bottom ends, the purposes of said grooves appearing later.

Within and near the bottom ends of said legs 13, but spaced a short distance above the base is an annular plate 16 which is secured to said legs in any suitable manner. To said plate is fixed the stator 17 of a variometer of any of the standard types. Within said stator is the rotor 18 having a shaft 19 which projects forwardly and between the legs of the front pair of legs to have bearing in an upright plate 20, secured to the top plate of the base near the front side of the centrally disposed circular body part 5 thereof. To that end of said shaft 19, beyond the bearing plate 20 is fixed a dial 21 having the usual graduations thereon which cooperate with a suitable mark on the front face of said plate 20.

To the under side of the top plate 2 of the

base 1 and spaced equal distances on each side of the vertical axis of the annular plate 16 are provided the usual "plug in" jacks 22 and 23, respectively which open through the vertical wall 4 of the base 1 to receive the associated plugs (not shown). Between the annular plate or ring 16 and the sockets 9 and 10, respectively, in the longitudinal plane of the major axis of the base and on the top plate thereof are rheostats 24 and 25 associated with the detector tube and amplifying tube, respectively. The coil parts 24^a and 25^a of said rheostats are arranged within the hollow base and are secured to the bottom surface of the top plate while the knobs 24^b and 25^b, respectively of said rheostats are mounted on the top surface of said top plate so that the same are disposed in positions most suitable for their convenient manipulation. Supported between the top ends of the legs 13, just below the block 14 is a transformer 26 of any well known kind. 27 and 28 indicate upright front and rear, substantially semi-circular plates of insulating material, each having a centrally disposed stem 27^a and 28^a, respectively, which fit and are secured as by means of screws in the front and rear grooves 15—15 of the block 14, as shown in Fig. 4. Secured in the side grooves 15^a—15^a of the block 14 are the reversely curved inner ends of oppositely disposed, horizontally extending members 29 which are arranged between and act to rigidly hold the plates 27, 28 in the desired spaced apart relation. The outer ends of the members 29 project beyond the periphery of the plates for a purpose to appear later, and coacting with said members in holding said plates in said spaced apart relation are screws 30—30 which extend through one plate and are threaded into the other plate as shown in Figs. 1 and 3. In the periphery of said plates are formed notches 31.

To the middle part of the front plate 27 and extending forwardly therefrom on its vertical median line, is a condenser 32 including the usual fixed and rotative spaced metallic plates 32^a and 32^b respectively and the supporting frame plates 32^c which are made of insulating material. Said condenser is secured to the front plate 27 by the same screws 33 which secure the fixed plates 32^a and frame plates 32^c of the condenser together.

To the shaft 34 of the condenser is secured a dial and turning knob 34^a, the dial having the usual graduations which co-operate with a mark on the front supporting plates of the condenser in the manner well known. On the rear plate 28 in line with the condenser, is mounted an inductance coil 35 the purpose of which is well known.

36 indicates an elastic tubular standard which is arranged midway between the two

plates 14 and 15 and is anchored at its bottom end to the block 14. Said tubular standard is preferably made of a tightly coiled spring and is reinforced at its top and bottom ends by short pieces of tubing 36^a—36^b respectively, as shown in dotted lines in Fig. 1. Said standard may be flexed or bent in the plane of the plates 27—28 and coacting means are provided on said plates and said standard to hold said standard in any desired angular position with reference to said plates. To this end there is provided on the standard 36 a block 37 which has forwardly and rearwardly extending pins 37^a—37^b upon which are pivoted oppositely facing U-shaped bails 38—38 which are adapted to engage in the notches 31 in the peripheries of the plates 27 and 28. Each bail carries a set screw 40 which when threaded inwardly to engage the block 36 is adapted to lock said bails in position in the engaged notches so as to hold the tubular standard in the desired angular position. The extreme flexed or bent over position of the standard is limited by one or the other of the members 29 and in said extreme flexed or bent over position one or the other of the bails 38 is hooked on the projecting end of said member 29.

Upon the top end of the tubular standard is located a socket 41 adapted to receive an electric light bulb 42. Said tubular standard provides an advantageous support for the aerial 43 of the radio receiving apparatus. As shown herein said aerial is of the loop type and includes an open or skeleton frame comprising top and bottom rings 44 and 45 and connecting members 46. In this instance, the bottom ring has rotative bearing upon the socket 41 so that the frame which tapers from bottom to top may be turned into different positions with respect to said socket. Upon the connecting members 46 of said frame are wound the spaced convolutions 47 of the aerial wire. Preferably, the open frame with the aerial wire wound thereon is covered by a suitable material 48 so that said aerial as a whole provides the shade for the lamp or light bulb.

The elastic tubular standard 36 provides a convenient conduit for the wires (not shown) leading to the light bulb 42 and it may also be used as a conduit for the wire connecting the aerial to the other elements of the receiving set. The wiring between the various elements may be arranged in accordance with the desired circuit and for the sake of clearness all wires or indications thereof have been purposely omitted from the drawings.

By releasing the set screws 40 and by lifting the bails 38 out of engagement from their respective notches, the standard 36 may be flexed or bent over into the desired angular position after which the bails are again entered into the corresponding notches in the

plates 27 and 28 and are then locked therein by tightening up on the set screws, which together with the contractile action of the standard locks the same in the desired adjusted position.

It is apparent that there is provided a neat compact combined radio receiving apparatus and lamp which is pleasing and ornamental in appearance and may readily be placed upon a table and the like. Furthermore, the aerial made as described, provides a shade which directs the light rays upon the various instruments or parts to be manipulated so that said parts are fully illuminated when "bringing" or "tuning" in a broadcasting station.

While in describing my invention, I have referred to certain details of construction, as well as the form and arrangement of parts, it is to be understood that the same is by way of illustration only and not by way of

limitation, because other arrangements might readily suggest themselves to those skilled in the art.

I claim as my invention:—

An apparatus of the kind described embodying therein a base, a plurality of legs rising from said base, a block to which the top ends of said legs are fixed, two spaced plates fixed to and rising from opposite sides of the said block, a flexible standard rising from said block and adapted to be flexed in the plane of said plates into different angular positions, latches carried by said standard to engage fixed parts of the plate to lock it in different angular positions and a loop aerial carried by said standard above the latches.

In testimony whereof, I have hereunto set my hand, this 1st day of August, 1924.

ALEXANDER B. KUPSCHE.
